ANTENNA SYSTEM

Louis John Heaton-Armstrong, London W. C. 2,
England, assignor to Standard Telephones and
Cables Limited, London, England, a British
company

Application January 8, 1943, Serial No. 471,703
In Great Britain January 12, 1942

4 Claims. (Cl. 250—11)

The present invention relates to antenna systems for blind approach arrangements for vehicles, for instance aircraft or ships, and of the kind in which the radiation distribution is oscillated about the approach path by means of auxiliary antennae adapted to be rendered effective as reflectors alternately so as to produce characteristic signals on each side of said approach path and to create along said path a zone or beam of equi-signal strength or continuous dash. The edges of this approach path, zone or beam of equi-signal strength are determined by the points where an indication of the characteristic signals first becomes apparent, and the width of the beam depends upon the inclination of the radiation diagrams to each other at the point of intersection. Such a well known system comprises a central directly fed antenna and two auxiliary parasitically excited antennae placed one on each side of said central antenna.

When the auxiliary antennae are keyed, that is are alternatively made to function as reflector, three field distributions are produced, namely, that for the energised antenna operating alone and two field distributions when the auxiliary antennae function respectively as reflector. The field strength of all three distributions must be equal in the equi-signal zone otherwise keying clicks will be heard in a receiving apparatus in that zone which is at right angles to the line joining the antennae. It is desirable for practical reasons in the landing of aircraft, for example that this beam or zone be made narrow.

The object of the present invention is to provide arrangements by which a narrower beam may be obtained than is possible with a single antenna and two reflectors. The antenna system according to the present invention comprises a plurality of antennae directly fed with exciting current and arranged so as to produce in the direction of the reflectors a field of greater strength than along said approach path and two auxiliary antennae arranged in alignment at right angles to said approach path one on each side thereof.

In the simplest and preferred embodiment of the invention, two antennae are fed with in-phase current and the two reflectors are similar and placed at equal distances from the fed antennae.

The invention will be better understood from the following description taken in conjunction with the accompanying drawing in which:

Fig. 1 shows diagrammatically a side view of the known arrangement of antennae;

Fig. 2 is a plan view of Fig. 1;

Fig. 3 is a plan view showing the simplest and preferred arrangement of antennae according to the present invention;

Fig. 4 shows the radiation distribution in the system of Fig. 1; and

Fig. 5 is a vector diagram referred to in the description.

Referring to the drawing, Fig. 1 shows a well-known system in which 0 is an antenna directly excited by the transmitter, 1 and 2 are parasitically excited reflectors spaced at a distance d from 0. The reflectors are opened at the centre by means of relays, only one reflector being connected at a time and there is a period while the relays are changing over when neither relay is closed. When the reflectors are keyed there are three field patterns produced, the first L, Fig. 4, for the antenna 0 and reflector 1 operating, the second N for the antenna 0 alone, and the third M for antenna 0 and reflector 2. The field strength from all three patterns must be equal on the equi-signal line AA which is the line at right angles to that joining the antennae. The patterns L, M and N must all pass through the same point on AA in order to eliminate keying clicks, and L and M must pass through the same point on AA to produce equal strength signals on AA.

30 The equations for the system will now be considered

Let

V_0 =Voltage applied to antenna 0

I_0 =Current in antenna 0

35 I_1 =Current in reflector 1

Z_{00} =Self impedance of antenna 0

Z_{01} =Mutual impedance between antenna 0 and reflector 1

Z_{11} =Self impedance of reflector 1

R_{11} =Resistance of reflector 1

40 θ_m =Angle of mutual impedance between antenna 0 and reflector 1

$$45 T = \tan^{-1} \frac{X_{11}}{R_{11}}$$

$$\bar{V} = \bar{I}_0 \bar{Z}_{00} + \bar{I}_1 \bar{Z}_{01}$$

$$0 = \bar{I}_0 \bar{Z}_{01} + \bar{I}_1 \bar{Z}_{11}$$

$$50 \bar{I}_1 = -\frac{\bar{I}_0 \bar{Z}_{01}}{\bar{Z}_{11}} = -\frac{I_0 Z_{01}}{Z_{11}} / (\theta_m - T)$$

Fig. 5 shows the currents vectorially.

55 It is assumed that the antenna is fed from a

constant current source so that the vector I_0 remains constant in magnitude whether the reflector is open or closed.

Under these conditions the resultant current I_R must equal I_0 in order that the three patterns shall cut on the equi-signal line.

This places a restriction on the width of the beam that may be obtained and the beam width varies with the value of d , having a minimum value for a particular value of d , other factors remaining constant.

In order to reduce this minimum beam width, the magnitude of the vector I_1 should be increased. This may be done in the following way, according to one embodiment of the present invention, reference being directed to Fig. 3.

Instead of one antenna 0 , as in Fig. 1, two antennae 0_1 and 0_2 are used in alignment with the equi-signal line and spaced apart a distance d_1 and fed with in-phase exciting currents. The resultant field radiated from 0_1 and 0_2 along the equi-signal line will with suitable distance d_1 be less than that radiated towards the reflectors 1 and 2. Hence the ratio of the field radiated from the reflector to that radiated from the antennae 0_1 and 0_2 on the equi-signal line may be made any value required by varying d_1 , assuming d_2 is fixed.

It is found that a minimum beam width occurs for a specific value of the ratio

$$\frac{\text{Field from antenna } 0_1 \text{ and } 0_2}{\text{Field from reflector 1}}$$

and also for a specific value of d_1 .

Since the ratio can also be varied by varying d_1 , it follows that the beam width can be adjusted to the minimum or other desired width by adjustment of the distance between the two excited antennae 0_1 and 0_2 . It is also found that there is a minimum beam width for a specific distance d_0 , that is the distance between a reflector and one of the fed antennae or d_2 . Thus for any given distance d_1 , the distance d_2 can be adjusted to give a minimum width beam.

Thus the distances d_1 and d_2 may be adjusted so that key clicks are eliminated and to give a minimum beam width. In one practical example a beam width of approximately 1.35° can be obtained with a spacing $d_0 = .375\lambda$ where λ is the working wavelength. d_1 is then approximately $.36\lambda$ and d_2 is $.66\lambda$. The loss of forward radiation is approximately 4.4 db as compared with the system shown in Fig. 1. The minimum beam width with the system shown in Fig. 1 when $d = .35\lambda$ is approximately 2.4° .

It will be understood by those skilled in the art that if the distances between the antennae and

reflectors are maintained constant adjustments of the point of intersection of the radiation distributions and the slope of the distribution diagrams at the point of intersection may be made by adjusting the electrical length of tuning of the reflectors.

Furthermore whilst the embodiment described has only two fed antennae it will be understood that any other number may be used and fed with suitably phased currents.

What is claimed is:

1. A directive antenna system for an aircraft approach system comprising a pair of reflector antennae arranged one on each side of a transmitting antenna structure and in alignment at right angles to the approach path, means for directly feeding said transmitting antenna structure with exciting current, means for alternately keying said reflector antennae, said transmitting antenna structure comprising a plurality of antennae arranged to produce a field of greater strength in the direction of the reflector antennae than along the approach path, the spacing of the reflector antennae from the transmitting antennae being adjusted so that at a point along the approach path the field strength of the transmitting antennae alone is substantially equal to the field strength of the combined fields and the transmitting antennae and one of the reflector antennae.

2. A directive antenna system for an aircraft approach system comprising two transmitting antennae arranged in line with the approach path, means for directly exciting said transmitting antennae with high frequency currents in the same phase, a pair of reflector antennae arranged one on each side of the said transmitting antennae and with a line connecting them at right angles to the approach path, the spacing of the reflector antennae from the transmitting antennae being adjusted so as to produce a minimum radiation beam width, and means for alternately keying said reflector antennae.

3. An antenna system as claimed in claim 2 wherein the reflector antennae are similar to each other and placed at equal distances from the transmitting antennae.

4. An antenna system as claimed in claim 2 wherein the distance between the two said transmitting antennae is so adjusted that the field strength at a point along the approach path due to these antennae alone is equal to the field strength at the same point due to the combined fields of the transmitting antennae and a reflector antenna.

LOUIS JOHN HEATON-ARMSTRONG.
